UNITED STATES PATENT OFFICE.

JESSE A. B. SMITH, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING-MACHINE AND SUPPORTS THEREFOR.

1,380,746.

Specification of Letters Patent. Patented June 7, 1921.

Original application filed June 21, 1917, Serial No. 175,996. Divided and this application filed May 17, 1920. Serial No. 382,166.

To all whom it may concern:

Be it known that I, JESSE A. B. SMITH, a citizen of the United States, residing in Stamford, in the county of Fairfield and 5 State of Connecticut, have invented certain new and useful Improvements in Typewriting-Machines and Supports Therefor, of which the following is a specification.

This invention relates to an improved 10 typewriting machine for writing manifold-form letters, and an improved machine support therefor.

In my prior Patent No. 1,237,716, dated 15 August 21, 1917, on which this is an improvement, the web, comprising several layers of work-sheets, was interleaved with carbon-sheets and fed to the platen. The web was continuous and preferably provided with printed forms, each constituting one 20 piece of work which, when completed, was torn off from the continuous web. The interleaved carbon-sheets were mounted on a carriage, so as to feed with the web while typewriting, but capable of being with- 25 drawn relatively to the web, so as to enable the bringing of a fresh portion of the web in register with the carbon-sheets, thus enabling the same carbon-sheets to be used repeatedly for a number of letters. In this way, a large number of form 30 letters could be written, with several copies of each letter, by using one set of carbon-sheets and a continuous web comprising several folds or layers.

In the patent to Fortin, No. 1,237,319, dated 35 August 21, 1917, it was shown how the carriage, on which the carbon-sheets were mounted, was formed in two parts, so that a portion on which the carbon-sheets 40 were directly mounted could be detached from the body of the carriage, thus enabling the web and the carbon-sheets to be detached and the typewriter used without that particular web.

In this present invention, there are provided 45 a plurality of carbon-sheet-supporting frames, two being shown. These supporting frames are used with different webs, preferably comprising strips of different 50 forms, so that, for one type of work, one web may be used, and, for an entirely different type, the other web may be used.

For the convenience of handling and interchanging the webs, the machine, *per se*, is

mounted on a table which supports, below 55 the top thereof and at the rear, a plurality of drawers, in which separate packs of webs may be placed, and from which they may be fed over the carbon carriage and its frame to the typewriter carriage and its platen. 60 There is provided one of the carbon-frame-carriers for each web, and they are of the detachable form, so that one may be interchanged for the other on the carbon carriage proper. 65

The drawers, storing the webs, are inclined slightly, so that the webs can be drawn off, layer by layer, without disturbing the under layers. Between the upper and lower drawers, a guide-rail is provided, 70 so that the lower web may clear the upper web, as the carbon frame for the upper web can most conveniently be rested right in back of the machine frame, above the tier of drawers. 75

When in use, the drawers are held in a position projecting from the rear of the table by struts mounted on the bottom of the drawers and engaging cross-pieces of the table. The struts are of graded size, 80 increasing from top to bottom, so that the lower drawer will project farther to the rear of the upper drawer. These struts are pivotally mounted so that they can be swung aside to permit the drawers to be shoved 85 in under the top of the table out of the way.

No claim is made herein to my improved machine stand or support, *per se*, claims to such invention having been made in my prior application, Serial No. 175,996, filed June 90 21, 1917, of which this case is a division.

Other features and advantages will hereinafter appear.

In the accompanying drawings, 95 Figure 1 is a perspective view, looking at it from the rear, showing the carbon frame for the upper web as detached, and the carbon frame for the lower web in place on the carbon carriage.

Fig. 2 is a vertical section, taken from the 100 front to rear, with the parts in position of Fig. 1.

The machine proper, indicated at 1, is supported about midway of the sides of a table 2. This machine includes the usual typewriting mechanism, and also a frame which extends rearwardly therefrom, to support a carbon carriage 3, which includes two or 105

more detachable carbon-carrying frames 4 and 5. This structure is more particularly described in Patents Nos. 1,237,716 and 1,237,319, above-mentioned.

5 In the present instance, there are shown two of the carbon-carrying frames, one indicated at 4 and the other indicated at 5. Each of the frames carries a set of carbon-sheets which are interleaved between the 10 folds of a web, which, for the carbon-carrying frame 4, is indicated at 6, and, for the carbon-carrying frame 5, is indicated at 7. The web 6, as shown in the drawings, is in position on the machine for writing, and 15 this web comes from a pack 8, located in the lower of a plurality of drawers 9 and 10. The upper drawer 10 carries a pack 11 of the web 7, which is connected to the carbon-carrying frame 5. The drawers 9 and 10 20 are slidingly mounted in guide-ways 12 and 13, so that they can be removed from the table, if necessary.

It will be noted that these drawers are inclined slightly downward and forward, 25 so that the upper layers of the webs can be drawn off without disturbing the lower layers. Between the upper web 7 and the lower web 6, there is provided a horizontal guide-rail 14, which enables the lower web 30 to clear the upper web and the drawer 10 for the same. The drawers 9 and 10 are made wide enough to leave plenty of room at the sides of the packs 8 and 11, so that as the carriage travels from side to side, the 35 web in position on the carriage can travel with the carriage at its upper end without disarrangement. The guide-rail 14 extends far enough on each side of the drawer 10 to prevent the lower web 6 from catching 40 on the side edges of the drawer 10.

When the device is in use, the drawers 9 and 10 are held in projecting position by struts 15 and 16, respectively. The struts engage cross-pieces 17 on the table when the 45 drawers are in their active position. The strut 15 is longer than the strut 16, so as to cause the lower drawer 9 to project farther rearwardly than the upper drawer 10, thus assisting the lower web 6 in clearing 50 the upper drawer 10. The struts 15 and 16 are pivotally mounted on the drawers 9, as by means of pins 18, to enable them to be swung to one side, permitting the drawers to be shoved into the interior of the 55 table, so as to be out of the way.

The utility of the device will be readily understood when taken in connection with the above description. Each of the drawers 60 9 and 10 is provided with a pack of web, each of which may be of its own particular character. That is to say, one drawer may contain a web of printed forms for one class of work, and the other drawer may contain a web of forms for a different class of work. 65 When it is desired to use the lower web 6,

as indicated in the drawings, it is placed on the carbon-frame 4, and the carbon-sheets interleaved between its folds. The frame 4 is then placed on the carbon carriage 3, and, after proper relative spacing 70 between the carbon-sheets and the folds of the web, the collated set is fed around the platen to the printing point. The letters are written according to the forms of the web, and cut off, one by one, with the proper 75 spacing of the carbon-sheets relative to the web. This is more particularly explained in the above-mentioned patents.

If it is desired to write forms of the character provided for on the upper web 7, then 80 the frame 4 is detached from the carbon carriage, and the web doubled over in the manner shown in connection with the web 7. This carbon-frame 4, with the web on it, can be placed out of the way, either on the 85 surface of the table, to one side of the machine, or in the lower drawer 9 itself. Then the upper web 7, with its carbon-carrying frame 5, may be placed on the machine. 90 This is done by attaching the carbon-carrying frame 5 to the carbon carriage 3, and, after a proper relative spacing of the carbon-sheets and the folds of the web, the manifold thus formed is fed around the 95 platen to be typewritten on.

The number of webs may be increased, if desired, and additional drawers provided. It will be noted that the drawers are arranged in substantial vertical register with the machine, so that they correspond to a 100 mid-position of the carriage in its travel, enabling the webs to move at their upper ends with the carriage, to either side of this mid-position, without disturbing the packs of webs in the drawers. The width of the 105 drawers also permits this sidewise motion of the webs at their upper ends.

The lower drawer 9 is held by its strut 15 and will project at the rear somewhat beyond the upper drawer 10, enabling the 110 lower web 6 when in use to clear the upper drawer 10 more easily. To force the drawers 9 and 10 within the confines of the table, it is merely necessary to swing the struts 15 and 16 to one side. In this position, the 115 drawers will be out of the way. When the struts are swung to one side, the drawers will slide forwardly in their guideways 12 and 13, and will be arrested when the sides of the struts strike against the cross- 120 pieces 17.

In this way, in addition to being able to write repeatedly a number of copies, of a given form, at one time, and repeat this form over and over again, a plurality of 125 forms may be used with the same machine, and kept in a position to be readily put on or taken off of the machine without any inconvenience. Thus, the operative can change rapidly from writing form-let- 130

ters of one type to writing form-letters of another type with the same machine, by simply detaching the frame carrying the carbon-sheets with the web thereon. This 5 maintains the carbon-sheets always interleaved between the folds of the web, so that either form can be picked up at a moment's notice and placed upon the machine, ready for work.

10 Variations may be resorted to within the scope of the invention, and portions of the improvements may be used without others.

Having thus described my invention, I claim:

15 1. The combination with a machine having a plurality of interchangeable sheet-frames for carrying carbon sheets interleaved with a manifold web, of a plurality of receptacles arranged in tier with said machine, each receptacle adapted to hold a pack of the manifold-form-web while being written on in the machine and attached to one of said frames individually, said frames and webs being interchangeable to working 20 positions on said machine without separating the carbon sheets and web while the latter is held in the receptacle whereby a rapid change may be made between different types of work by merely interchanging said 25 frames.

30 2. The combination with a machine, arranged to do manifold work, having a plurality of interchangeable carbon-sheet frames for carrying carbon sheets interleaved with a manifold web, a support for the machine carrying a receptacle for holding a web on one of said frames in a pack, while being written on by the machine, a second receptacle at a different level for supporting a second web on another of said frames in a pack, the frames and webs being interchangeable to writing position without removing the latter from the receptacles, and a guide projecting beyond the side margins of said receptacles, and located between the same, for clearing one of said webs.

35 3. An article of manufacture, comprising means for writing in alternation on either of a plurality of fan-fold webs, and comprising a typewriting machine, a plurality of carbon-sheet-carriages each carrying carbon sheets interleaved with a web usable alternatively upon said typewriting machine, a receptacle or magazine from which one of 40 said webs is led to said carbon-sheet-carriage, a second receptacle or magazine for the other fan-fold web to hold the latter between the typewriting machine and the reach of the first web which extends up from 45 the first magazine to the typewriting machine, and supporting means for said carbon-sheet-carriages when detached from the typewriting machine and maintained in association with their respective webs.

50 4. An apparatus to facilitate the type-

writing of sets of manifold forms fed in succession from the same series or in alternation from different series, at the election of the operative, comprising, in combination, a typewriting machine into which said forms 55 may be fed to be typed, said machine comprising a number of interchangeable web-frames, each capable of maintaining a set of forms of a manifold web and a set of interleaved carbon-sheets in assembled relation 60 ready for insertion in said machine, said frames being attachable to, and removable from, said machine with said sets of forms and carbon-sheets assembled therewith, and a like number of receptacles in which packs 65 of webs, each comprising a succession of sets of forms as a continuation of the set assembled with interleaved carbon-sheets by one of said frames, may be stored ready for use, and from any one of which parts of the 70 stored web may be fed to said machine, together with the associated carbon-sheets, after inserting the corresponding web frame 75 therein.

5. An apparatus to facilitate the type-writing of sets of manifold forms fed in succession from the same series or in alternation from different series, at the election of the operative, comprising, in combination, a typewriting machine into which said 80 forms may be fed from the rear to be typed, said machine comprising a number of interchangeable web frames, each capable of maintaining a set of forms of a manifold web and a set of interleaved carbon-sheets 85 in assembled relation ready for insertion in said machine, said frames being attachable to, and removable from, said machine with said sets of forms and carbon-sheets assembled therewith, and a support or table for 90 said machine having therein a like number of web receptacles, each opening to the rear of said support, and in which packs of web, each comprising a succession of sets of forms as a continuation of the set assembled with 95 interleaved carbon-sheets by one of said frames, may be stored ready for use, and from any one of which parts of the stored web may be fed to said machine, together with the associated carbon-sheets, after inserting the corresponding web frame 100 therein.

6. An apparatus to facilitate the type-writing of sets of manifold forms fed in succession from the same series or in alternation from different series, at the election 105 of the operative, comprising, in combination, a typewriting machine into which said forms may be fed from the rear to be typed, said machine comprising a number of interchangeable web frames, each capable of 110 maintaining a set of forms of a manifold web and a set of interleaved carbon-sheets in assembled relation ready for insertion in said machine, said frames being attachable to, and removable from, said machine 115

with said sets of forms and carbon-sheets assembled therewith, and a support or table for said machine having therein a like number of web receptacles, each opening to the 5 rear of said support, and in which packs of web, each comprising a succession of sets of forms as a continuation of the set assembled with interleaved carbon-sheets by one of said frames, may be stored ready for use, 10 and from any one of which parts of the stored web may be fed to said machine, together with the associated carbon-sheets,

after inserting the corresponding web frame therein, said receptacles being disposed one above another in said support, there being 15 also a guide projecting beyond the side margins of said receptacles, and located between the same for clearing one of said webs as it is fed from side to side.

JESSE A. B. SMITH.
